CLAIM

The ornamental design for an arm chair as shown and described.

DESCRIPTION

FIG. 1 is an elevated, front-right perspective view of a first embodiment of the new design for an arm chair;

FIG. 2 is an elevated, rear-left perspective view of the embodiment of FIG. 1;

FIG. 3 is a top plan view of the embodiment of FIG. 1;

FIG. 4 is a bottom plan view of the embodiment of FIG. 1.

FIG. 5 is a right side elevational view of the embodiment of FIG. 1, the left side elevational view being the mirror image thereof;

FIG. 6 is a lowered, front-right perspective view of the embodiment of FIG. 1;

FIG. 7 is a front elevational view of the embodiment of FIG. 1; and

FIG. 8 is a rear elevational view of the embodiment of FIG. 1.

FIG. 9 is an elevated, front-right perspective view of a second embodiment of the new design for an arm chair;

FIG. 10 is an elevated, rear-left perspective view of the embodiment of FIG. 9;

FIG. 11 is a top plan view of the embodiment of FIG. 9;

FIG. 12 is a bottom plan view of the embodiment of FIG. 9.

FIG. 13 is a right side elevational view of the embodiment of FIG. 9, the left side elevational view being the mirror image thereof;

FIG. 14 is a lowered, front-right perspective view of the embodiment of FIG. 9;

FIG. 15 is a front elevational view of the embodiment of FIG. 9; and,

FIG. 16 is a rear elevational view of the embodiment of FIG. 9.

(Continued)

Broken lines included within the drawings represent unclaimed subject matter that forms no part of the new design.
